INVENTOR

Louis T. Bergh

BY *Berney S. Webster*
ATTORNEY

UNITED STATES PATENT OFFICE.

LOUIS T. BERGH, OF FAIROAKS, CALIFORNIA.

JACK.

Application filed October 17, 1924. Serial No 744,160.

To all whom it may concern:

Be it known that I, LOUIS T. BERGH, a citizen of the United States, residing at Fairoaks, county of Sacramento, State of California, have invented certain new and useful Improvements in Jacks; and I do declare the following to be a full, clear, and exact description of the same, reference being had to the accompanying drawing and to the characters of reference marked thereon, which form a part of this application.

This invention relates to improvements in lifting or spreading jacks, and particularly to a small type adapted to be used for spreading the spokes away from the fellys of motor vehicle wheels to enable spoke tightening shims, such as are now on the market, being placed therebetween.

The principal object of my invention is to provide a jack having besides the usual rotatable or relatively rotatable screw stem by means of which the head and foot pad of the jack are separated, a means for imparting an additional separating movement to the head and foot in such a manner that not only can great excess separating pressure be applied without the use of a corresponding amount of physical effort, but this additional movement takes place without any tendency to rotation between the relatively rotatable parts of the jack.

In this manner not only may the head and foot of the jack be separated to an extent greater than is otherwise possible with an equal expenditure of physical effort, but owing to the elimination of the rotative tendency with this additional movement, the parts against which the head and foot of the jack bear are not subjected to the rubbing and twisting effect inevitably had when the jack parts tend to rotate as in ordinary jack construction.

This feature is especially of value in connection with operations on automobile wheels, on which an enamel and high polish is frequently ruined by the twisting movement of a jack pad applied thereagainst.

In carrying out the above object I make use of the same principle as that shown in my co-pending application for patent, Serial No. 712,772, filed May 12th, 1924, as will be clearly seen hereinafter.

While this jack is especially designed and shown for use in connection with automobile wheels it is to be understood that the same construction may be incorporated in

jacks for any purpose where the additional spreading feature would be of value.

A further object of the invention is to produce a simple and inexpensive device and yet one which will be exceedingly effective for the purpose for which it is designed.

These objects I accomplish by means of such structure and relative arrangement of parts as will fully appear by a perusal of the following specification and claims.

In the drawings similar characters of reference indicate corresponding parts in the several views:

Fig. 1 is a fragmentary outline of an automobile wheel showing my jack as applied thereto.

Fig. 2 is an enlarged sectional elevation of the jack.

Fig. 3 is a fragmentary section on the line 75 3—3 of Fig. 2.

Referring now more particularly to the characters of reference on the drawings, the numeral 1 denotes a hollow body member tapped at one end and solid at the other. 80 From the solid end a central pin 2 projects outwardly and is loosely connected to a pad 3 adapted to abut against the felly 4 of the wheel between any two of the spokes 5.

Screwed into the tapped end of the body 85 1 is a screw stem 6, whose outer end is unthreaded and is slidably mounted in the bore 6^a of a foot block 7. This foot is wedge shaped at its outer end to seat between the spokes 5 at their junction with each other, 90 as shown in Fig. 1.

The stem is prevented from rotating in the foot but is allowed to have limited longitudinal movement relative thereto by means of a pin 8 screwed into the foot on 95 one side thereof and extending into a longitudinal slot 9 cut in the stem 6.

Turnably mounted in the foot transversely thereof and extending through the bore 6^a, is a pin 10 having a head 11 on one end to 100 which a wrench may be applied. Intermediate its ends this pin is cut away and made out of round, as shown at 12, for a length at least equal to the diameter of the stem 6. Thus that portion of the pin is cam shaped 105 in cross section.

In operation this pin is initially turned so that its flat portion faces the stem 6 and the latter rests thereagainst. A wrench is then applied to the member 1, whose sides 110 are polygonal, so as to cause the same to be advanced on the threads of the stem 6, and

hence the pad 3 and foot 7 are separated. When this operation has been carried out to the desired point, or until the resistance is such as to cause the pad or foot to tend to twist and it is hard to turn the member 1, a wrench is applied to the head 11 of the pin 10 and the latter is given a half turn or less. This causes the periphery of the pin farthest from its central axis to bear against the adjacent end of the stem, instead of the flat portion of the pin, as was previously the case. The foot and stem will therefore be separated a distance equal to the distance between the plane of the flat portion 12 relative to the axis of the pin and the plane of the normal periphery thereof relative to said axis.

It will also be evident that this movement of the foot and stem takes place in a plane longitudinally of said members, and no rotative tendency, either of the foot stem or body 1, is had.

This cam member 12 may of course be designed to give a very small lift and a consequently large amount of leverage, or it may provide for a greater lift with a correspondingly smaller leverage. Since, however, the main object of this cam is to provide not a great lift but a great power or leverage, the cam would preferably be designed as mentioned in the first instance.

From the foregoing description it will be readily seen that I have produced such a

device as substantially fulfills the objects of the invention as set forth herein.

While this specification sets forth in detail the present and preferred construction of the device, still in practice such deviations from such detail may be resorted to as do not form a departure from the spirit of the invention as defined by the appended claims.

Having thus described my invention what I claim as new and useful and desire to secure by Letters Patent is:

1. A jack comprising a body, a stem screwed therein, a block having a bore into one end of which the outer end of the stem slidably projects, the stem terminating short of the inner end of the bore, and a cam concealed within the bore and on which the stem rests, the cam projecting through and being journaled in the sides of the block whereby to enable the cam to be turned.

2. A jack comprising a body, a stem screwed therein, a block having a blind bore into the open end of which the outer end of the stem slidably projects, the stem terminating short of the inner end of the bore, a cam concealed within the bore and on which the stem rests, said stem having a longitudinal groove disposed inwardly of the outer end of the block, and a radial pin secured in the block and projecting into the groove.

In testimony whereof affix my signature.

LOUIS T. BERGH.
